UNITED STATES PATENT OFFICE.

NELSON MUSLAR, OF WORCESTER, MASSACHUSETTS, ASSIGNOR, BY MESNE ASSIGNMENTS, TO NORMAN ROBINOVITZ, OF WORCESTER, MASSACHUSETTS.

LABELING MACHINE.

Application filed September 28, 1923. Serial No. 665,441.

This invention relates to a machine for pasting labels upon bottles, cans and other similar articles. I have shown my invention as applied to a machine of the single bottle manual feed type but many features of my invention are not limited to such use and may be embodied to advantage in other types of labeling machines.

It is the general object of my invention to provide an improved and simplified labeling machine which will be more reliable in operation, better adapted to a wide range of work, less expensive to build and more easily assembled and repaired.

To the attainment of this general object, important features of my invention relate to the following matters, namely; an improved label holder and label conveying or transfer mechanism therefor, improved devices for moving the label conveying plates or pickers, novel mechanism for actuating the label wipers and for adapting them to different shapes of bottles, auxiliary devices for applying labels on the necks of bottles, improved stopping and starting mechanism for the machine, and novel mechanical connections for actuating the several parts.

My invention further relates to certain arrangements and combinations of parts which will be hereinafter described and more particularly pointed out in the appended claims.

A preferred form of the invention is shown in the drawings, in which—

Fig. 1 is a side elevation of my improved labeling machine;

Fig. 2 is a front elevation of certain parts of the machine, looking in the direction of the arrow 2 in Fig. 1;

Fig. 3 is a rear elevation of the wiping mechanism, looking in the direction of the arrow 3 in Fig. 1;

Fig. 4 is a rear elevation of a modified form of wiping mechanism;

Fig. 5 is a sectional elevation of the label conveying and applying mechanism, looking in the direction of the arrow 5 in Fig. 1;

Fig. 6 is a sectional front elevation showing parts of the pasting mechanism and of the driving mechanism therefor, looking in the direction of the arrow 6 in Fig. 1;

Fig. 7 is a partial sectional side elevation, showing the starting and stopping mechanism;

Fig. 8 is a detail plan view, looking in the direction of the arrow 8 in Fig. 7;

Fig. 9 is a plan view of the stopping cam;

Fig. 10 is a side elevation of the actuating mechanism for the label stripper, looking in the direction of the arrow 10 in Fig. 6;

Fig. 11 is a side elevation of the actuating mechanism for the pasting roll, looking in the direction of the arrow 11 in Figs. 5 and 6;

Fig. 12 is a sectional front elevation showing the actuating mechanism for the label pickers;

Fig. 13 is a sectional side elevation of the actuating mechanism, taken along the line 13—13 in Fig. 12;

Fig. 14 is a view similar to Fig. 12 but showing the parts in a different position;

Fig. 15 is a plan view of the label holder;

Fig. 16 is a side elevation thereof, looking in the direction of the arrow 16 in Fig. 15;

Fig. 17 is a detail sectional front elevation taken along the line 17—17 in Fig. 16;

Fig. 18 is a detail side elevation of a device for moving the label holder to inoperative position;

Fig. 19 is a detail sectional plan view, taken along the line 19—19 in Fig. 16;

Fig. 20 is an enlarged detail side elevation looking in the direction of the arrow 20 in Fig. 19;

Fig. 21 is a plan view of a modified form of label holder;

Fig. 22 shows an additional device for wiping a label upon the neck of a bottle, and

Fig. 23 is a detail sectional plan view, looking in the direction of the arrow 23 in Fig. 22.

Referring to the drawings, my improved labeling machine as shown herein comprises a base 30 (Fig. 1) supporting a post or standard 31 and providing bearings for a main shaft 32 upon which a drive pulley 33 is freely rotatable. The inner face of the hub of the pulley 33 is provided with a series of notches 34 (Fig. 7) each adapted to receive the flattened end of a plunger 35 slidable in a recess 36 in a collar 37 fixed to the shaft 32, these parts forming a clutch connection between the pulley and the shaft.

A spring 38 tends to move the plunger 35 outward to operative position. A stud 39 projects from the side of the plunger 35

through a slot in the wall of the recess 36 and holds the flattened end of the plunger 41 in radial alignment with the notches 34. A cam plate 40 (Fig. 9) is mounted on the upper end of a plunger 41 which is vertically slidable in a fixed bearing 42 (Fig. 7) and is connected by a forked lever 43, link 44, lever 45, cross shaft 46, and cross rod 47 (Fig. 8) to a pair of levers 48 upon which is mounted a foot plate or pedal 49 (Fig. 1). A spring 50 (Fig. 7) normally holds the pedal in raised position, with the plunger 41 correspondingly raised and the cam 40 in position to withdraw the clutch plunger 35.

When the pedal 50 is depressed, the cam 40 is drawn downward out of engagement with the stud 39, whereupon the spring 38 advances the plunger 35 and its flattened end enters the first notch 34 which is thereafter aligned therewith. The machine will continue to operate as long as the foot plate is held in depressed position but as soon as the foot plate is released, the cam 40 moves upward and stops the machine upon the completion of its revolution, by withdrawing the plunger 35 from the hub of the driving pulley. I have thus provided a very convenient single revolution clutch and starting mechanism, which may also be used to keep the machine in continuous operation.

The main shaft 32 (Fig. 1) is operatively connected to drive a considerable number of different mechanisms which will now be separately described. These mechanisms include label pickers 52, a pasting roll 53, (Fig. 5) a label stripper 54 (Fig. 1) and label wipers 55, for each of which parts novel and improved actuating mechanism is provided.

A label holder 56 is mounted upon a forwardly projecting head 57 on the post 31 and the labels are successively removed from the label holder by the pickers 52, previously coated with glue or paste by the pasting roll 53. The pickers 52 bring the label down to the bottle where it is held by the stripper 54 while the pickers move upward and the wipers 55 advance to engage the label and wipe it smoothly upon the bottle.

The operation of the pickers is shown in Figs. 5, 12 and 14. The pickers 52 comprise a pair of forwardly extending parallel plates shown in side elevation in Fig. 1 and secured for vertical adjustment at the upper end of a slide 60 (Fig. 5) mounted in fixed guide-ways 61 and connected by a link 62 to a crank pin 63. The crank pin 63 is mounted upon a block 64 slidable radially in a forked arm 65 fixed to the main shaft 32. A spring 66 normally pushes the block outwardly and outward movement thereof is limited by an end plate 67. A roll 68 (Fig. 13) is mounted on the rear side of the block

64 and is positioned in the cam groove 69 (Fig. 12) of a fixed side cam 70. The groove 69 is circular in outline for about three quarters of its circumference and has a depressed or inwardly curved portion 71 in the remaining quarter.

The roll 68 is moved around the fixed cam 70 in the direction of the arrow α in Fig. 12 and when starting from its highest position, the crank pin 63 receives a regular crank motion for about three quarters of its revolution, during which time the label L (Fig. 14) is conveyed from the label holder to the label-applying position shown in Fig. 12 and the pickers 52 are thereafter raised to the pasting position shown in full lines in Fig. 14. At this point, the roll 68 enters the depressed or inwardly curved portion 71 of the fixed cam, thereby shortening the crank radius and retarding the pickers for a brief period, during which the pickers are coated or gummed by the pasting roll 53. This provision of a retarded movement during the pasting operation is of great advantage and constitutes an important feature of my invention.

The stripper 54 for removing the label L from the pickers 52 is actuated by the mechanism shown in detail in Figs. 6 and 10. A cross shaft 74 (Fig. 6) is mounted in bearings 75 on the base 30 and is driven from the main shaft 32 by a pair of spiral gears 76 and 77 of equal size. A cam 78 (Figs. 6 and 10) is secured to the cross shaft 74 and is engaged by a cam roll 79 on a link 80 which is forked at its lower end and is thus guided by the cross shaft 74. The upper end of the link 80 is pivoted at 81 to an arm 82 connected to swing the stripper 54 about a stud or pivot 83.

The link 80 is preferably formed in two parts which are yieldingly separated by a spring 84, thus permitting the stripper to yieldingly engage the bottle. The yielding movement of the parts of the link 80 is limited by a cross pin 85, and a spring 86 (Fig. 6) is provided which holds the link with its cam roll 79 in yielding engagement with the cam 78.

The cam 78 is so formed and timed that the stripper 54 will be held in raised position while the label is descending, after which it will be quickly swung downward to engage the label and hold it against the bottle while the pickers rise and the wipers advance to wipe the label upon the bottle. The stripper is then again moved quickly upward before the descent of the next label.

A bottle support 88 (Figs. 1 and 10) is mounted for vertical adjustment upon a pair of studs 89 and 90 and may be secured in position thereon by a set screw 91. A stop 92 for the bottom of the bottle is adjustable forward and rearward by a bolt and slot connection to the support 88.

It is necessary to provide a thin coating of paste or glue upon the upper surfaces of the pickers after each label is removed therefrom and for this purpose I provide a pasting roll 53 and the actuating mechanism therefor shown in Figs. 1, 6 and 11. The paste box or reservoir 95 is mounted on the post 31 and is provided with a roller 96 (Fig. 6) rotatably mounted therein.

10 The roller 96 is driven through spur gears 97 and 98 a sprocket wheel 99 (Fig. 1) and a chain 100 from a second sprocket wheel 101 mounted on the cross shaft 74. The roller 96 is thus continuously rotated during 15 the operation of the machine. A scraper 102 (Fig. 6) is yieldingly mounted on posts or studs 103 and may be adjusted toward or from a roller 96 by wing nuts 104.

10 The pasting roller 53 (Fig. 5) is mounted 20 on a roll shaft 105 rotatable in yielding bearings 106 at the upper end of a pair of rock arms 107. The arms 107 are fixed to a cross rod 108 supported in bearings in the machine frame and one of the arms 107 has 25 a bolt and slot connection with a bell crank 109 (Fig. 11) so that it may be angularly adjusted relative thereto. A forked link 110 is pivoted at 111 to the bell-crank 109 and is provided with a cam roll 112 engaged by 30 a cam 113 on the cross shaft 74. A spring 114 holds the roll yieldingly against the cam.

35 The parts are so disposed that the pasting roll 53 is positively moved outward to apply paste to the pickers 52 and is yieldingly moved rearward to engage the roller 96 and is thoroughly coated with paste, gum or glue thereby. The forward movement of the roll 53 is timed to correspond to the retarded upward movement of the pickers 52 previously 40 described, thus providing a sufficient time interval for the transfer of paste or glue to the pickers.

45 The mechanism for actuating the wipers 55 is shown particularly in Figs. 2, 3 and 13. The wipers 55 are mounted upon bell-cranks 120 pivoted at 121 to the upper end of a slide 122. The slide 122 is guided for vertical movement upon a pair of posts 123 and is connected by a link 124 to a crank arm 125 fixed to the front end of a short horizontal shaft 126. The shaft 126 is rotatable in fixed bearings aligned with the main shaft 32 and at its rear end is provided with a cam 127 having a slotted arm 128 projecting therefrom. The slot 129 in the arm 128 receives the projecting forward end of the crank pin 63 (Fig. 13) which actuates the picker slide 60. The shaft 126 is thus rotated 55 in unison with the main shaft 32 and the crank arm 125 regularly reciprocates the wiper slide 122.

60 The lower arms 130 of the bell-cranks 120 are connected by links 131 (Fig. 3) with a slide plate 132 mounted in guideways 133

on the wiper slide 122. A cam roll 134 on the lower end of the slide plate 132 engages the cam 127 previously described and is actuated thereby to give the wipers 55 a swinging movement upon their pivots 121 70 independent of the vertical movement of the slide 122. It will be evident that many different combinations of movements of the wipers 55 may be obtained by suitably designing the cam 127.

75 A spring 135 is interposed between portions of the slide 122 and the slide plate 132 and maintains the latter in yielding engagement with the cam 127.

80 In the modified construction shown in Fig. 4, the wipers 140 are mounted upon bent levers 141 pivoted at 142 to the wiper slide and having depending arms 143 provided with cam rolls 144. The auxiliary slide 145 is provided with cam surfaces 146 and 147 engaged by the rolls 144 as the slide 145 moves relative to the wiper slide. By a suitable selection and arrangement of cam surfaces, the wipers 140 may be given almost any desired combination of movements, making 90 this form of wiper mechanism particularly well adapted for wiping labels upon rectangular or irregular shaped bottles.

95 The label holder and delivery mechanism for my improved machine is clearly shown in Figs. 15 to 20 and as shown therein is arranged for feeding diamond shaped labels. A sleeve or support 150 is mounted for vertical sliding movement upon studs 151 and 152 projecting upwardly from the head 57. 100 A stud 153 projects laterally from the support 150 and a lever 154 is pivotally mounted thereon. The lower end of the lever 154 is provided with a cam slot 155 (Fig. 18) through which projects a roll 156 pivoted on 105 a stud 157 fixed in the head. When the lever 154 is in the position shown in Fig. 18, the label box is in its lower or operative position, but when the lever is swung upward in the direction of the arrow *d* in Fig. 18, 110 the stud 153 is raised, causing corresponding upward movement of the label box to inoperative position. It is thus easily possible to interrupt the label feed while permitting the other portions of the mechanism 115 to continue in operation.

120 A cross frame member 158 is mounted upon a stud 159 projecting forwardly from the support 150 and may be angularly adjusted thereon by adjusting screws 158^a 120 (Figs. 6, 15 and 16) which engage the under side of the frame member 158. A pair of horizontal rods 160 are secured in the ends of the frame member 158 and a pair of guide bars 161 and 162 are slidably mounted on 125 the rods 160 and support the label guides 163. The bars 161 and 162 may be secured in any desired spaced relation upon the rods 160 by set screws 164. The guides 163 are provided with vertically extending guide 130

rods 165 (Fig. 16) and these guide rods are provided at their lower ends with obliquely disposed inwardly extending lugs or projecting portions 166 (Figs. 19 and 20).

5 The labels L are positioned by the rods 165 and are supported upon the lugs or projections 166. The angular or oblique position of the projections 166 is found to greatly facilitate successive delivery of labels therefrom.

10 A bracket 167 (Fig. 16) is mounted for angular adjustment upon a stud 168 extending upwardly from the cross frame member 158. A bar 169 extends forwardly from the bracket 167 and provides a support for a casting 170 slidably mounted thereon and secured in adjusted position by a binding screw 171 (Fig. 17). A feeding block or weight 172 is secured to the lower end of a feed rod 173 which is vertically slidable in the casting 170. At its upper end, the rod 173 has a lock plate 174 having its opposite end angularly disposed and provided with a recess through which projects a rod 175 extending upward from the casting 170.

15 The plate 174, due to its angular construction, will slide freely downward on the rod 175 but will resist upward movement when pressure is applied thereto at the outer end thereof. The plate thus follows the feed rod 173 as the rod and feed block move downward with the labels and in each new position thereof the lock plate 174 resists upward movement of the rod and block 20 and holds the labels for firm engagement by the pickers 52. A friction spring 176 on the rod 173 will act to hold the rod and block in extreme raised position when drawn upward into the casting 170.

25 The cross bar 161 (Fig. 15) is provided with upwardly extending arms 180 having bearings at their upper ends which may receive a cross rod 181 (Fig. 21), upon which is threaded a pair of guide arms 182. The rod 181 is provided with right and left hand threads so that the distance between the guide arms 182 may be adjusted by rotation of the threaded rod 181. This construction is particularly adapted for holding square 30 or rectangular labels, with label guide rods 165 mounted upon the arms 182 and also directly upon the cross bars 161 and 162. Adjustment is provided in both directions so that the rods 165 will engage and position rectangular labels of any ordinary dimensions.

35 Having thus described my improved machine and the details of construction thereof, it is believed that the method of operation will be readily understood. The labels being placed in the label box and the box being lowered to operative position, the machine is set in operation by depressing the pedal 49 after a bottle B has been placed upon 40 the bottle support 88. The pickers 52 move

upward from the position shown in Fig. 12 to that shown in Fig. 14, at which point their movement is retarded while the pasting roll 53 applies a film of paste or glue thereto. The pickers then continue their upward movement to the position shown in dotted lines in Fig. 14 where they engage the lowermost label L and withdraw the same from the label box as they commence their downward movement. The pickers then descend to the position shown in Fig. 12, carrying the label L therewith. The stripper 54 is then swung downward to engage the label and hold it against the bottle B as the pickers commence their next upward movement. The wipers 55 are moving upward as the label is stripped from the pickers and as the pickers rise, the wipers move inward from the position shown in Fig. 12 to that shown in Fig. 14. The wipers then move 50 downward while in their inward position and smoothly apply the label to the rounded surface of the bottle, the wipers being formed of rubber or other flexible material which permits them to adapt themselves to 55 the shape of the bottle.

60 If the bottle is rectangular or irregular in shape, the cam construction shown in Fig. 4 may be utilized to give the wipers additional inward and outward movements as 55 they move downward. While the label is thus being applied to the bottle, the stripper 54 swings upward out of the path of the next descending label. A fresh bottle is 65 then inserted in the machine and the operation is repeated. By releasing the foot plate or pedal, the machine will automatically stop at the end of each revolution, and by holding the pedal down, the machine may be 70 operated continuously so long as the operator can provide fresh bottles for the machine.

75 In Figs. 22 and 23, I have shown an attachment by which an additional label may be placed upon the neck of a bottle at the same time that the body label is applied. For this purpose, auxiliary wipers 185 are mounted upon arms 186 pivoted upon studs 187 in the main wiper arms 120. A plunger 188 is slidably mounted in an opening in 80 the arm 120 and is pressed yieldingly rearward by a spring 189. At its rear end the plunger 188 is provided with a roll 190 positioned for engagement by a cam projection 191 on the picker slide 60. The front end of the plunger 188 engages a lateral projection 192 on the auxiliary wiper arm 186. The parts are so timed that the cam 191 will 85 engage the roll 190 as the wipers commence their downward movement and as the slide 60 commences its upward movement. By such engagement, the plunger 188 is pushed forward, rocking the wiper arm 186 and causing the auxiliary wipers 185 to apply a 90 label to the neck of the bottle.

Having thus described my invention and the advantages thereof, I do not wish to be limited to the details herein disclosed otherwise than as set forth in the claims, but what

5 I do claim:—

1. In a labeling machine, a paste box, a driven roller rotatable therein, a pasting roll, means including a cam and a cam roller to move said pasting roll from paste receiving

10 to paste delivery position and return, means to yieldingly hold said cam and roller in engagement with each other, and means to positively rotate said roll when in contact with said driven roller.

15 2. In a labeling machine, a paste box, a roller rotatable therein, means to drive said roller including a gear fixed thereto, a pasting roll, a pinion fixed to rotate with said roll, and means including a cam, and a cam roller in yielding engagement therewith to move said roll to and from paste receiving position, said pinion engaging the gear on said roller for positive rotation thereby when said pasting roll is in contact with said driven roller.

20 3. In a labeling machine, a pair of pickers, a picker slide, a driven shaft, a variable crank arm on said shaft, and a cam track, and means to connect said arm to said slide and to said cam track.

25 4. In a labeling machine, a pair of pickers, a picker slide, a driven shaft, an arm on said shaft, a block slidable in said arm, a crank pin on said block, a link connecting said crank pin to said slide, and a fixed cam effective to vary the radial position of said block and crank pin.

30 5. In a labeling machine, a pair of pickers, a picker slide, a driven shaft, an arm on said shaft, a link connecting said arm and said slide, a fixed cam, and means controlled by said cam effective to radially vary the point of connection between said arm and said link.

35 45 6. In a labeling machine, a pair of label wipers, means including a slide on which the wipers are mounted to give said wipers a reciprocating vertical movement, and additional means connecting said wipers and said slide to give said wipers an in-and-out movement to apply a label on a bottle.

40 50 55 7. In a labeling machine, a pair of wipers, a slide on which said wipers are mounted, means to give said slide a vertical reciprocating motion, and additional means including a plate removably mounted on said slide

and connected to said wipers to give said wipers an in-and-out motion on said wiper slide.

8. In a labeling machine, a pair of label wipers, a slide on which said wipers are mounted, a slide plate mounted on said wiper slide, and separate means to actuate said slide and said slide plate.

9. In a labeling machine, a pair of label wipers, a slide on which said wipers are mounted, a slide plate mounted on said wiper slide, means to give motion to said wiper slide from a regularly driven crank, and a cam to give said wiper plate an independent additional movement on said wiper slide.

10. In a labeling machine, a pair of label wipers, a slide on which said wipers are mounted, a slide plate mounted on said wiper slide, links connecting said wiper plate to said wipers, and separate means to actuate said slide and plate independently as to time.

11. In a labeling machine, a pasting roller, rocking arms supporting said roller, and means to rock said arms to move said roller between paste receiving and paste delivery positions, said means including a cam-actuated arm having a bolt-and-slot connection with one of said rock arms, whereby angular adjustment of said cam-actuated arms is permitted.

12. In a labeling machine, a label holder including a label feeder, a manually operated cam lever effective to raise said holder and to retain the same in raised position above label feeding position, and a friction spring effective to hold said feeder above its label feeding position.

13. In a label holder, a plurality of label positioning rods, and means to support said rods in engagement with the different edges of said labels, said rods having label supporting portions obliquely disposed at all times relative to the adjacent edges of said labels.

14. In a label holder, a plurality of label positioning rods, means to support said rods in engagement with the different edges of said labels, said rods having label supporting portions obliquely disposed at all times relative to the adjacent edges of said labels, and means to laterally adjust said rods to receive labels of different sizes.

In testimony whereof I have hereunto affixed my signature.

NELSON MUSLAR.
